UNITED STATES PATENT OFFICE

2,595,249

YIELDING RELEASE FOR MILLS AND CRUSHERS

Oscar C. Gruender, Milwaukee, Wis., assignor to
 Nordberg Manufacturing Company, Milwaukee,
 Wis., a corporation of Wisconsin

Application October 20, 1949, Serial No. 122,456

1 Claim. (Cl. 241—290)

1 My invention relates to an improvement in crushers and has for one purpose to provide an improved spring release for gyratory crushers.

Another purpose is to provide an improved spring release assembly which is bodily readily removable from the crusher.

Another purpose is to provide a bowl and bowl support assembly which, with an appropriate yielding release, may be removed as a unit from the crusher and may be returned as a unit to the crusher.

Other purposes will appear from time to time in the course of the specification and claim.

I illustrate my invention more or less diagrammatically in the accompanying drawings, wherein:

Figure 1 is a side elevation;

Figure 2 is a vertical axial section with parts omitted; and

Figure 3 is a plan view of the crusher bowl, 20 with parts broken away.

Like parts are indicated by like symbols throughout the specification and drawings.

Referring to the drawings, 1 indicates a circumferential main frame member shown as having an outwardly extending top flange 2 provided with downwardly offset or extending bosses 3 which surround apertures 4 having lower inwardly conic shoulders 5 and reduced aperture portions 6. The details of the rest of the main frame do not of themselves form part of the present invention. I illustrate, however, a lower central hub 7 connected by any suitable spiders or supports 8, 9 to the circumferential main frame 1.

Removably secured in the hub 7 is the normally fixed crusher shaft 10, which is shown as having a downwardly tapered portion 11, seated in a similarly formed aperture in the hub 7. The shaft 10 is shown as having a generally cylindrical outer surface 12. Rotatable about it is the eccentrically apertured sleeve 13 having an inner bearing liner 14 and any suitable bottom bearing ring 15. The ring 15 rests upon any suitable bearing ring 16, supported upon the upper surface of the hub 7. The eccentric sleeve 13 carries toward its lower end the gear 18, which is shown as in mesh with the pinion 19 on any suitable drive shaft 20. It will be understood that when power is applied to rotate the shaft 20 from any suitable power source, not herein shown, the result of the rotation of the pinion 19 is to rotate the eccentrically apertured sleeve 13 about the outer bearing surface 12 of the upper portion of the fixed shaft 10.

2

Rotatable about the exterior cylindrical surface 21 of the eccentrically apertured sleeve 13 is the head structure generally indicated as 22. It includes a downwardly extending sleeve 23 with a liner 24 which surrounds the outer surface 21 of the eccentrically apertured sleeve 13. The head is also provided with a downwardly spherical portion 25 opposed to a suitable spherical bearing ring 26 mounted on or forming a part of the frame. The head also has skirt portions 27, 28 and a generally spherical surfaced sealing member 29 which extends into a circumferential sealing cavity 30, mounted in the main frame. If it is desired, water may be circulated through the annular trough 30, whereby a sealing relation is maintained with the member 29 which, at all times, extends below the surface of the water in the trough 30.

Any suitable feeding means not herein shown may be mounted upon the upper portion of the head 22.

It will be understood that the relation of the surfaces 12 and 21 is such that the rotation of the eccentrically apertured sleeve 13 gives the head structure 22 a gyratory movement about the center marked X. This center is a point where the axis Y of the surface 12 and the axis Z of the surface 21 meet. 22a is any suitable wearing part, or ring, or mantle which may be removably mounted upon the head 22. The details of the attachment do not of themselves form part of the present invention and are not shown. It will be understood, however, that in response to the rotation of the drive shaft 20, the crushing or grinding head 22, with its mantle 22a and with any suitable feeding means, is gyrated about the center X.

Lubrication may be provided through any suitable means, the details of which do not form part of the present invention. I illustrate, however, an axial oil duct 35 in the shaft 10; a circumferential exterior oil channel 36, a generally radial oil passage 37 in the eccentrically apertured sleeve 13, a circumferential exterior channel or groove 38, and an oil passage or duct 39 extending to the spherical bearing formed by the opposed parts 25 and 26.

Resting upon the main frame flange 2 is the removable bowl supporting and centering ring, generally indicated as 40. It is shown as including a downwardly extending flange 41, which circumferentially embraces the outer face of the main frame flange 2. It also includes an upwardly extending centering flange 42, the purpose of which will later appear, and a bowl support cen-

tering flange 43. The flange 43 has a generally cylindrical outer surface 44 which may, if desired, be slightly barrel shape, upon which surface the below described bowl structure may at times tilt. The inner face of the flange 43 is generally conic, as indicated at 45.

Seated upon and centered by the flange 44 is the bowl supporting ring 46. It has a downwardly open channel 47 conforming generally to the conic surface 45, as at 48. It has an outer cylindrical surface 49 opposed to the outer surface 44 of the flange 43. The support 46 also has outwardly extending portions 50 apertured as at 51 to permit the passage therethrough of bolts or compression members 52. Each such bolt is shouldered as at 53, the shank of each bolt passing through an appropriate aperture in the annulus 40, the head 53 abutting the lower surface of the annulus 40 and being positioned within a socket or aperture 4 in the main frame flange 2. Below each head 53 is a reduced portion 55 which extends through the aperture 6 which may receive any suitable locking nuts 56. The ring or bowl support 46 has an upwardly extending generally cylindrical wall 60 extending upwardly from the outer edge of a ridge or offset 61. The member 46 is inwardly threaded as at 62.

Surrounding and outwardly spaced on the support 46 is the outer ring or housing element 65. It is centered about the flange 42 and may be adjusted by shims 66. At its upper end it is provided with an inner abutment flange 67, apertured as at 68 to permit the passage therethrough of the bolts or compression members 52. 69 are any suitable nuts or abutments opposed to the upper surface of the flange 67. The space between the upper edges of the members 65 and 46 may be enclosed by a flexible housing formed of rubber or fabric members 70, 71 connected at their outer edges, for example by any suitable ring or angle member 72.

Adjustable within the bowl support 46 is the bowl structure generally indicated as 75. It has an outer generally cylindrical component 76, outwardly screw-threaded as at 77, to mesh with the threads 62. It has a bottom component 78 to which the bowl liner or wear-taking members 79 may be suitably secured. The member 80 connects the inner edge of the members 78 with the upper edge of the outer cylindrical portion 76. It may also carry any suitable, removable wear-taking hopper 81.

82 is an outwardly extending top flange sealed against the inner surface of the wall 60, as at 83. 84 is a downward extension of the cylindrical portion 76, which is sealed as at 85 to an opposed flange 86 outwardly extending from the bowl support 46. 87 are adjusting screws which pass through appropriately screw-threaded apertures in the flange 82, and abut the upper surface of the ridge 61. They are shown as having upper square heads 88 and as being provided with any suitable lock nuts 89. These lock nuts are laterally accessible through windows 90 in the generally cylindrical upward extension 91 of the bowl. It will be understood that when the screws 87 are released, the bowl structure 75 may be rotated in relation to the bowl support 46. The result is an upward or downward adjustment. When the desired adjustment is reached, the bolts 87 may be screwed into position. The square heads 88 are freely accessible from above. The lock nuts 89 may be tightened, being readily accessible through the windows 90.

The upward extension 91 is exteriorly provided

with a plurality of teeth 100. The upward extension 60 is provided with an upwardly extending notch or depression 101. 102 generally indicates a locking member having a shank 103 extending into the socket or recess 101 and having a plurality of teeth 104, adapted to extend into the teeth 100 formed in the exterior of the member 91. The lock 102 is effective to prevent relative rotation of the bowl structure 75 and of the bowl support or adjusting ring 46.

It will be realized that whereas I have described and shown a practical and operative device, nevertheless many changes may be made in size, shape, number and disposition of parts without departing from the spirit of my invention. I therefore wish my description and drawings to be taken as in a broad sense illustrative or diagrammatic, rather than as limiting me to my precise showing herein. It will be understood, for example, that my spring release may be employed with a wide variety of crushers, including so-called cone and gyratory crushers, the particular crusher parts herein shown being indicated merely as a matter of illustration.

The use and operation of my invention are as follows:

I illustrate a main frame and gyrating mechanism, including the fixed shaft 10 and the eccentrically apertured sleeve 13, which are adapted for the support and gyration of a crushing head or cone. In the particular mechanism herein described and shown, a crushing cavity is defined between the mantle 22a on the head and the bowl liner 19 supported on the bowl 75. Material is fed from above into the upper, inner feed receiving aperture of the cavity defined between the two feed members. The gyration of the head subjects the material to be crushed or ground to a series of crushing nips. The crushed material flows outwardly from the circumferential discharge outlet of the crushing cavity. It is advantageous, and under some circumstances vitally necessary, to provide a yielding release which will prevent breakage or jamming in the event any uncrushable material is present in the crushing cavity. Such yielding release may be necessitated by packing of the material in the cavity when crushing wet or by the passage of hard or oversize particles, including drill bits, dipper teeth, or other uncrushable members.

An advantage of the structure herein shown is that I have included a yielding release in a bowl and bowl supporting structure which can be readily removed as a unit from the main frame. 55 The ring 40 rests upon and surrounds the main frame flange 2. If desired, it could be positively secured to the flange 2, although under most circumstances a mere press fit is satisfactory. The bowl support proper 46 is centered upon the flange 43 and the bolts or compression members 52, shouldered as at 53, are movable with the ring 40. To remove the entire assembly, including the bowl support and the bowl, all that need be done is to release the nuts 56. When these are removed, the entire bowl assembly, including the ring 40, can be upwardly lifted and removed for repair, adjustment or replacement without in the least disturbing the compression of the springs 95. Where it is important to keep a continuous flow of material, as in a large mill, a spare assembly may be maintained ready and may be quickly dropped into position, with the result that the flow of material through the mill need be interrupted for only a very short period.

It will be clear, for example from Figure 2, that

the parts are held normally in the position in which they are shown in Figure 2 by the expansion or thrust of the spring 95, one of which surrounds each bolt or compression member 52. The springs are compressed between the flanges 67 and 50. The springs are completely housed within the housing member 65.

In event that uncrushable material passes through the crushing cavity, the bowl support 46 will tilt upwardly in relation to the flange 43. The result will be a slight inward movement of the upper edge of the cylindrical wall 60. Since the members 70 and 71 are of flexible material, they give slightly but still maintain an adequate seal for the upper end of the space in which the springs 95 are positioned. There is no damaging entry of dust or grit. The tilting is permitted and guided by the formation of the flange 43. Its outer face 44 may, if desired, be slightly barrel shaped, as in the corresponding part 20 of United States Letters Patent No. 2,358,038 assigned to the assignee of the present application. However, under many circumstances this is not necessary, as adequate clearance may be provided between the opposed surfaces 44 and 49.

I provide a compact and efficient bowl supporting structure in which the bowl may be readily adjusted upon release of the lock screws 87. The annular shims 66 may be of varying thickness and offer a convenient means for varying the tension of the springs 95, compressed between the overlapping flanges 50 and 67. Any suitable means may be used for clamping the vertical fabricated ring 70 in position in relation to the housing members 65. I illustrate, for example, the 35 clamping ring 70a. The fact that the bolts 52 are provided with shoulders 53 abutting the ring 40 makes it possible to compress the springs 95 independently of the main frame. This permits the entire bowl structure, including the springs, to 40

be removed from the main frame without at all disturbing the compression of the springs.

I claim:

In a bodily removable bowl supporting unit for gyratory crushers, a ring formed and adapted to rest upon an upper frame flange of a crusher, the ring having an inwardly located, tapered bowl centering flange, a bowl support tiltably mounted on said flange, a bowl adjustably mounted on said support, an outer housing resting in sealed relationship upon said ring and surrounding said bowl support, a sealing closure between upper parts of said housing and bowl support, compression members extending through said ring each 15 said compression member having portions extending downwardly below said ring and portions extending upwardly from said ring within the space between the bowl support and the housing, said compression members having abutments engaging upper portions of said housing and lower portions of said ring, springs about said compression members, said springs being under compression between upper portions of said housing and lower portions of said bowl support, the lower portions 20 of said compression members being formed and adapted to be positioned in securing relationship with the upper frame portion of the crusher upon which the ring rests.

OSCAR C. GRUENDER.
